SUPPORTING STAND FOR GARMENT FORMS

Application filed January 9, 1929. Serial No. 331,334.

This invention relates to supporting stands for garment or dress forms and particularly to that type of stand in which the body of the form is adjustable to various heights.

5 The present invention relates to adjustable forms of the type known in the trade as automatic forms and in which the supporting pedestal is made of a pair of tubular telescopic members that are slid longitudinally relatively to each other and are locked in adjusted position by means of a pair of wedge-shaped, internal, expanding members, the actuation of which to lock and unlock the stand is controlled through a spring actuated rod 15 by a foot pedal, the tubular members being constructed to perform a shock absorbing or dash pot function.

While garment forms having pedestals of this type are extensively used, the constructions heretofore employed for such pedestals and for the locking means are subject to many objections among which may be noted the failure of the locking means to grip and hold securely the parts in adjusted position; 20 the tendency of the locking members to drop away from their proper positions and to fall into the tubular members, thereby necessitating a dismantling of the pedestal to recover the locking members and then a reassembling of the parts; the failure of the spring rod, which is connected to one of the locking members, to function properly, the spring exhibiting a tendency to bind on said rod and in addition losing its resiliency after 25 a relatively short period of use; the failure of the tubular members to perform properly the shock absorbing or dash pot action which they are intended to perform in which case breakage of the parts frequently occurs; the 30 tendency of many of the parts to break or otherwise get out of order under ordinary usage, and the difficulty of manufacturing and assembling the parts.

As large numbers of these garment forms 45 are used in the garment industry and by highly paid skilled workers, it is of the utmost importance that they function properly and require but a minimum amount of attention on the part of the operative. If, for example, the locking members become disengaged

while the operative is engaged in fitting or draping a garment thereon, and the body of the form drops, the operative's time is wasted in readjusting the device. Likewise, if the locking members fail to release or grip immediately when the foot pedal is operated the operative's time is wasted.

In view of the above the principal object of the present invention is to provide a new and improved construction for a device of the character set forth that will be certain and reliable in the functioning of its locking members, in the performance of the shock absorbing or dash pot action, and in the operation of the spring actuated rod; that will be of simple and sturdy construction, with the parts thereof so connected and arranged that dislodgment thereof out of their proper positions can not occur; that will require but a minimum amount of machining operations in the manufacture thereof, and that may be assembled quickly and easily by relatively unskilled labor in a minimum time.

The above and other objects will appear more fully from the following more detailed description and by reference to the accompanying drawing forming a part hereof and wherein Fig. 1 is a central vertical section through a supporting stand constructed in accordance with the principles of my invention; Figs. 2 and 3 are sections on the lines 2-2 and 3-3 of Fig. 1, respectively, and Fig. 4 is a section on the line 4-4 of Fig. 2.

As shown in the drawings the numeral 10 indicates the legs of the supporting base for the pedestal which radiate from and support at a spaced distance from the floor a hollow boss 11. Projecting laterally from the members of an adjacent pair of legs 10 and preferably formed integrally with said legs is a pair of stub pins 12 which form bearings for a pedal 13. The pedal 13 is formed between its ends with a pair of laterally projecting half bearings 14 which, as clearly shown in the drawings, are adapted to co-operate with the pins 12 for pivotally supporting the pedal member. Located between the bearings 14 and projecting downwardly from the underside of the pedal is a block or lug 15 which, when the pedal is placed in position upon the

pins 12, is located between the ends of said pins and co-operates therewith to prevent transverse movement of the pedal. At its inner end the pedal terminates in a substantially horizontal flat portion 13^a which engages the lower end of a spring pressed rod 16. The outer end of the pedal is formed to provide a treadle portion 13^b which portion is provided with a plurality of elongated transverse slots 13^c. At the edge of each slot the treadle portion is formed with an upwardly projecting edge 13^d. These edges provide in effect a corrugated surface that prevents the operator's foot from slipping off the pedal when it is actuated.

The sides of the slots 13^c, as clearly shown in Fig. 1, are preferably tapered so that the slots are wider at the bottom thereof than at the top. This construction is employed to facilitate the casting of the pedal and also to obviate the tendency of dirt from the sole of the operator's foot to collect in the slots and clog the same.

Extending into the bore of the hollow boss 11 is the lower end of a tubular member 17. A short distance from the lower end of said member a spring reaction block 18 is located within said member and, in order to hold said block securely locked in position within the tube 17, said block is provided with a peripheral groove into which the metal of the tube is forced as indicated by the reference character 19. The tube 17 preferably fits within the boss 11 with a neat press fit and, in order to insure against longitudinal movement of said tube to said boss, a set screw 20 is screwed into the metal of the boss and bears at its inner end against the outer wall of the tube in alignment with the groove 19.

Confined between the block 18 and a cup-shaped member 21 is a coil compression spring 22 which spring encircles the rod 16. The cup-shaped member 21 is of a diameter such that it will slide freely within the tube 17 and which is held against movement relatively to the rod 16 by any suitable means such as the nut 23. It will be noted that the spring 22 is entirely enclosed and concealed within the tube 17 and the cup-shaped member 21.

At its upper end the tube 17 passes into a second tubular member 24 which is telescopically associated with the tube 17. The upper end of the tube 24 is closed by a block 25 which is press fitted into said tube 24. The block 25 has secured therein the lower end of a post or rod 26, the upper end of which carries the body 27 of a garment form.

In devices of the character to which the present invention relates the body 27 is adjusted and locked in position at a desired distance from the floor. Movement of the body 27 to and from the floor is effected by sliding the tube 24 longitudinally relatively to the tube 17. The means for locking the two tubes in adjusted position comprises an

internal expanding locking device which consists in the present case of a pair of cylindrical blocks 28, 29. These blocks, as clearly shown in Fig. 1, are superimposed one upon the other within the tube 24 and their meeting or contacting faces are similarly inclined so that said blocks will co-operate to produce a wedging action when they are moved relatively longitudinally of the tube 24 and towards each other. Both of the blocks are provided with a central bore through which the rod 16 passes loosely. The lower block is supported upon the upper end of the tube 17, a washer 30 preferably being interposed between the lower face of said block and the top of the tube.

The upper block 29 is normally urged towards the block 28 by the pressure of the spring 22 which, as will be readily understood, exerts through the cup-shaped member 21 and nut 23 a pressure upon the rod 16 which tends to move the same in a downward direction. This downward movement of the rod 16 is communicated to the block 29 by a nut 31 screwed upon the upper end of said rod. A washer 32 is preferably interposed between said nut and the top of the block 29.

In order to avoid imparting sudden shocks to the device when the locking blocks 28, 29 are released, the upper portion of the tube 24 is employed, in co-operation with the parts now to be described, to perform a dash pot function. A leather washer 33, which is cup-shaped in accordance with the usual construction of such devices, is placed upon the rod 16 above the nut 31, washers 34 being placed below and above said leather washer. Seated upon the top washer 34 is a block 35 of compressible resilient material such as rubber or the like. This compressible block is adapted to be forced against the upper washer 34, and to be held against movement longitudinally of the rod 16 by means of a nut 36, a lock nut 37 being provided to hold the nut 36 in adjusted position. In order to prevent too rapid leakage of air from the upper end of the tube 24 and about the block 25, a cork 38 is fitted snugly within said tube 24 and is forced into the tube until it contacts with the block 25.

It is desirable with a device of the character described to provide means for preventing the telescopic tubes 17 and 24 from being disengaged when the body 27 is raised to its uppermost limit. For this purpose the block 28 is made of slightly larger diameter than the tube 17. The lower end of the tube 24 is slightly flared outwardly to provide a small flange 39. A washer 40 encircles the tube 24 and rests upon the flange 39. Detachably connected to the washer 40 by any suitable means such as the screws 41 is another washer 42, the inner diameter of which is less than the outer diameter of the block 28 and such

that the washer 42 will slide freely upon the tube 17.

As a further precaution against subjecting the stand to shocks or blows should the dash pot fail to function to check the downward movement of the body 27, a buffer spring 43 surrounds the lower end of the tube 17 and rests upon the upper face of the boss 11, a washer 44 preferably being placed upon the upper end of said spring 43.

The operation of the device is as follows: The parts are shown in Fig. 1 of the drawing in their locked position the spring 22 pressing at its upper end upon the block 18 which it will be remembered is held against movement within the tube 17. The lower end of the spring 22 pressing against the cup-shaped member 21 and nut 23 forces the rod 16 downwardly. It will be understood that the rod 16 slides freely through the central aperture of the block 18. The force exerted downwardly by the spring 22 is communicated through rod 16, nut 31 and washer 32 to the upper block 29, thus holding the lower inclined face of the block 29 pressed tightly against the upper inclined face of the block 28. It will be noted that the central bores of the blocks 28, 29 are considerably larger than the diameter of the rod 16 so that lateral movement of said blocks is permitted. As the lower block 28 is held against movement by the tube 17 the force exerted by the spring 22 acting on the inclined meeting faces of the blocks 28, 29 will cause said blocks to be moved laterally and to be pressed into tight engagement the inner bore of the tube 24. As the diameter of the outer cylindrical surface of the blocks 28, 29 is but slightly less than the diameter of the bore of the tube 24 the blocks will grip said tube with a large contacting surface area and will securely hold the tube 24 against longitudinal movement and in fixed relationship to the tube 17. If the operator wishes to change the adjustment of the body 27, the foot pedal 13 is depressed by placing the foot upon the treadle portion 13^a thereof. This will cause the pedal 13 to be rotated upon its bearings 12, 14, thus moving the inner end 13^a of the pedal upwardly and causing the rod 16 to be moved upwardly against the pressure of the spring 22. As the rod 16 moves upwardly the pressure of the spring 22 is taken up by the inner end of the foot pedal and therefore the pressure is released upon the blocks 28, 29. This will permit the blocks 28, 29 to move inwardly transversely of the tube 24 and release their frictional holding engagement with said tube.

The tube 24 and body 27 can therefore be slid longitudinally or vertically to bring the body 27 the desired distance from the floor. When the blocks 28, 29 are released as above described and the weight of the body 27 and the parts connected thereto is not supported

by the operator, it is obvious that the force of gravity will cause the upper members to descend. In such descent air will be trapped between the leather washer 33 and the upper end of the tube 24 which is closed by the cork 38 and block 25. The pressure of the air trapped between the washer 33 and cork 38 is sometimes considerable, particularly if the upper portion is allowed to drop quickly. The cushioning effect however with the construction herein disclosed is certain and reliable, the cork 38 preventing a rapid escape of the air. The cork 38 is however not entirely air tight and will permit a very slow escape of the air when the pressure thereof mounts considerably. The result is that the upper part of the device will slowly descend to its lowermost limit of travel.

The provision of the compressible block 35 enables the leather washer 33 to be adjusted so as to secure just the proper functioning of said leather washer.

It will be noted that the inner diameter of the spring 22 is considerably larger than the outer diameter of the rod 16, thereby not only avoiding any binding of the spring upon said rod but also permitting said spring to be so constructed that it will be sturdy and strong in its action and capable of withstanding long periods of use.

The bores of the blocks 28 are preferably made tapered, as shown in the drawings, so that said blocks may be cast without resorting to the use of cores in the casting operation, thus materially reducing the cost of manufacture.

It will also be noted that the washer 42 will co-operate with the block 28 to act as a stop for limiting the upward movement of the parts. As it is however sometimes desirable to dismantle the telescoping tubes, the washer 42 is detachably secured to the lower end of the tube 24 by the screws 41. If then it becomes desirable to dismantle the device or to obtain access to the locking blocks, it is only necessary to unscrew the screws 41 after which the upper tube 24 and the parts carried thereby can readily be removed from the lower portion of the device.

While the construction herein disclosed forms a satisfactory and practical commercial embodiment of the invention, it will be understood that many changes, variations and modifications may be resorted to without departing from the spirit of the invention.

I claim:

1. In a supporting stand for garment forms or the like, an upper and a lower tubular member arranged in telescopic engagement, a pair of cylindrical locking wedges supported on top of said lower tubular member and located within said upper tubular member, each of said wedges being provided with a central bore, a rod passing through said lower tubu-

lar member and the bores of said wedges, a spring for normally urging said rod in one direction, means for communicating such movement of said rod to one of said wedges and manually operable means for moving said rod in an opposite direction.

2. In a supporting stand for garment forms or the like, an upper and a lower tubular member arranged in telescopic engagement, a pair of cylindrical locking wedges supported on top of said lower tubular member and fitting slidably within said upper tubular member, each of said wedges having a central bore and an inclined side face in contacting engagement with the similarly inclined face of the other wedge and means for normally forcing said inclined faces of said wedges together and thereby holding a large surface area of the cylindrical peripheries of said wedges in contact with a similar area of the inner wall of said upper tubular member, said means comprising a rod extending through the central bores of said wedges, a spring and a pair of abutments on said rod, one acting on said spring and the other on one of said wedges.

3. A supporting stand as set forth in claim 2 in which the upper tubular member has detachably secured to it a stop for co-operation with one of said wedges for limiting the movement of said tubular members out of telescopic engagement.

4. In a supporting stand for garment forms or the like, a supporting base, a tubular member fixed within said base, a reaction block secured within said tubular member, a compression spring housed within said member and contacting at its upper end with said block, a cup shaped washer surrounding the lower end of said spring and slidably within the lower end of said tubular member, a rod passing through said tubular member, said block, said spring and said washer, and having its lower end projecting below said washer and tubular member, an abutment on said rod against which said cup-shaped washer projects, an upper tubular member in telescopic engagement with said lower tubular member, a pair of wedges each having a central bore, an outer cylindrical periphery and an inclined side face arranged one above the other within said upper tubular member and encircling said rod, an abutment on the upper end of said rod for engagement with the upper one of said wedges and a foot pedal pivotally mounted on said base for engagement with the lower projecting end of said rod.

5. A supporting stand as set forth in claim 4 in which the supporting base is provided with a plurality of floor legs, two of which are provided with laterally projecting bearing stubs, and the foot pedal is provided with a pair of bearing surfaces for pivotal engagement with said bearing stubs.

6. A supporting stand as set forth in claim

2 in which the upper tubular member is provided at its upper end with means to prevent escape of air and a pump washer is secured to said rod for engagement with the inner wall of said upper tubular member and producing a dash pot effect when said upper tubular member moves downwardly upon the lower tubular member.

7. A supporting stand as set forth in claim 2 in which the upper tubular member is provided at its upper end with means to prevent escape of air and a pump washer is secured to said rod for engagement with the inner wall of said upper tubular member and producing a dash pot effect when said upper tubular member moves downwardly upon the lower tubular member, a block of compressible resilient material is mounted on said rod in engagement with said pump washer and an adjusting means is provided for compressing said compressible block against said washer to vary the effective engagement thereof with said upper tubular member.

8. A supporting stand as set forth in claim 4 in which the supporting base is provided with a plurality of floor legs, two of which are provided with laterally projecting bearing stubs, and the foot pedal is provided with a pair of bearing surfaces for pivotal engagement with said bearing stubs and with a projection located between the ends of said stubs for co-operation with said stubs to prevent lateral movement of said pedal.

9. In a garment form supporting stand, a supporting base having a hollow boss, a pair of telescopically engaged tubular members, a pair of wedges for engaging one of said members and locking said members in adjusted position, an operating rod extending through said members and said boss, and projecting at its lower end below said boss, a bearing in said boss for said rod, a coiled spring surrounding the lower end of said rod and confined between said bearing and an abutment on said rod for normally urging said rod in a direction to cause said wedges to lock said tubular members, a cup shaped member, in which the lower end of said spring is seated, slidably mounted in said hollow boss, said spring being completely enclosed within said cup shaped member and boss, and a pedal for moving said rod against the action of said spring to release said wedges, said cup shaped member co-operating with said boss to prevent lateral distortion of said rod.

10. A garment form supporting stand of the type wherein a pair of telescoping tubular members mounted on a supporting base having a hollow boss are adjustable to vary the height of said form and are locked in adjusted position by a pair of wedges under the control of a spring actuated operating rod and a pedal, characterized by said boss and wedges being provided with aligned central bores, a bearing block having a central

aperture, said rod passing through said central aperture of said bearing block and the center of the bores of said wedges and tubular members, and means for securing said bearing block within said boss, and the central aperture of said block fitting said rod with a neat sliding fit and preventing lateral distortion thereof.

In testimony whereof I have hereunto set
10 my hand.
